UNITED STATES PATENT OFFICE

CHARLES W. HUNTER, OF LOS ANGELES, CALIFORNIA.

• **TIMER**

Application filed March 27, 1929. Serial No. 350,230.

This invention relates to a current interrupting device for the ignition system of an internal combustion engine.

An object of the invention is to provide improved means for housing the operating parts of the device whereby access may more readily be had to any part which needs repair or replacement.

A further object of the invention is to provide an improved interrupting device and ignition system therefor which are particularly adapted for use on the engines of aeroplanes and which may be safely and quickly repaired, or have parts thereof replaced without difficulty, and without stopping the operation of the engine, while an aeroplane is in flight.

With the above and possibly other objects in view, the invention includes a casing where-
20 in is housed the mechanism of the device, said casing having doors which form a part of the wall thereof, a portion of said mechanism being attached to each of said doors to be moved therewith into and out of its opera-
25 tive position, the opening movement of said doors bringing the mechanism carried thereby into a conveniently accessible position for replacement or repair, and also affording ready access to the portion of the mechanism
30 mounted within the stationary part of the casing.

Referring to the accompanying drawings which illustrate what is at present deemed to be a preferred embodiment,

35 Fig. 1 is a plan view of the device, the upper side of the cover being removed, the door being shown in full lines in the closed position and in dotted lines in the open position. Fig. 2 is a side elevation, partly in mid sec-

Fig. 2 is a side elevation, partly in mid-section on line 2-2 of Fig. 4.

Fig. 4 is a plan view of Fig. 2.

Fig. 5 is a section on line 5-5 of Fig. 1.

45 Referring in detail to the drawings to the
timer shaft 7 is secured a multiple cam 8,
said cam in the illustrated embodiment of
the invention being a disk having six equi-
distant circumferentially arranged rounded
50 cam points 8° with which cooperate two op-

positively disposed contact arms 9 and 10 of identical construction. Said contact arms are respectively mounted upon pivot posts 11 and 11^a which extend up from the base plate 12^b. Terminals 13 and 14 are provided to cooperate with these arms.

The pivot posts 11 of the contact arm 9 is secured to the segmental door 12 which, when closed, forms a continuation of the casing wall 6, said door being pivoted to the casing at 13°, the free end of said door closing down upon a recess 13^a and being provided with a latch 15. To the inner surface of the said door 12 is attached a curved leaf spring 16 which engages one of the limbs of the L-shaped contact arm 9 thus tending to move the contact point 17 of said arm into engagement with the terminal 13. 60 65

Said terminal 13 is manually adjustable, being carried by a winged bolt 20 which has a screw-threaded engagement with an internally threaded boss 21 formed on door 12, a winged lock nut 22 being provided for said bolt 20, and to hold the conducting plate 23 in place. Oppositely to the door 12 the casing is provided with a similar door 12^a, upon the inner side of which are mounted the contact arm 10, adjustable terminal 14, contact point 17^a, pivot post 11^a, spring 16^a, and door hinge 13^a, all of which function the same as the corresponding parts which have already been described. 70 75 80

In Fig. 3 is shown an instrument board 30 upon which the timer casing 6 is mounted, said instrument board being spaced at a considerable distance away from the motor 31. The gearing 32 of said motor is timed properly to rotate to driving shaft 33 which is operatively connected with the timer shaft 7 by means of a universal joint 34. This arrangement makes it more convenient for the mechanic to repair the device during flight. 90

Each door is normally locked by a locking bolt 40 inserted into the lower side of the casing near the free end of said door. Said belt is normally held in the locking position by a leaf spring keeper 41 which is pivoted to the casing by a screw 42.

In Fig. 5 is shown, in sectional detail, an upstanding pin 11 fixed to a support 12^b to 100

form a pivot for arm 9 which is removably placed on said pivot. The swivelled spring arm 11^a normally guards said arm from displacement.

5 Current from a suitable source, in the present instance a battery 40^b, is supplied to the high tension coils 41 and 41^a, connected by wire 41^w. The illustrated embodiment of the invention shows two sets of current interrupting devices, one set being supplied through the high tension coil 41 and the other set being supplied through the high tension coil 41^a. The set of devices supplied through the coil 41 comprises the spring actuated terminal 42 which wipes upon a ring 43 mounted in the rotary head. 41^b is a lead for coil 41^a, and 41^c is a lead for coil 41. These leads are normally in circuit with the doors 12^a and 12 as shown in Fig. 1.

20 Head 44 is provided with another outwardly extending arm 45 through which extends a lead 46 to conduct current from said ring 43. Said lead 46 is constructed and arranged to cooperate with a series of terminals 47 whereby one member of each of the pair of spark plugs which is located in each engine cylinder is supplied with current.

25 The other set of contact devices comprises the centrally located spring actuated terminal 50 which engages a contact 51, the head 44 being provided with an arm 52 through which passes a conductor 53 to conduct current from said contact 51. Said conductor 53 cooperates with a series of terminals 54 whereby the other member than that already mentioned of each of the pair of spark plugs in the individual engine cylinders is supplied with current.

30 In the illustrated embodiment of the invention the doors on which part of the circuit-making and circuit-breaking elements are mounted, are shown hinged to the casing but it is not intended that the invention shall be limited to doors of this character, but 45 other closure devices for openings in the casing wall may be provided to perform the function of these doors, without departing from the spirit of the invention.

35 One of the doors may be opened and the 50 electrical equipment carried on the inner face thereof be repaired without stopping the engine, because each engine cylinder is provided with two sets of ignition devices, and each of these devices is in a different system from 55 the other, the opening of either door affecting the circuit of only one of these ignition systems.

An extra door may be provided on which is 60 mounted a duplicate set of circuit-breaking elements, and this door may be substituted for a door which is removed on account of faulty operation of the circuit breakers carried thereby.

Claims:

65 1. In a device of the class described, a cur-

rent interrupting mechanism comprising a distributor head and a casing within which said mechanism is normally housed, said casing having a door which forms a part of the wall thereof, a portion of said mechanism being attached to the inner side of said door to move therewith into and out of operative position.

70 2. In a device of the class described, multiple system current interrupting means comprising a distributor head and a casing within which said interrupting means is normally housed, said casing having a plurality of doors, a portion of said interrupting means being attached to each of said doors to move therewith into and out of operative position.

75 3. In a device of the class described, a casing having a relatively large opening through its wall, a door for said casing forming a closure for said opening, circuit-making and circuit-breaking elements part of which are mounted on the inner side of said door to be brought into an accessible position when said door is opened, and cooperating contacts carried by said door and casing, said contacts completing the circuit through the aforementioned elements carried by said door when it is closed and when it is open interrupting the circuit of which they form a part.

80 4. In a device of the class described, a casing having a relatively large opening through its wall, a door for said casing forming a closure for said opening, circuit-making and circuit-breaking elements part of which are mounted on the inner side of said door to be brought into an accessible position when said door is opened, and cooperating contacts carried by said door and casing, said contacts completing the circuit through the aforementioned elements carried by said door when it is closed and when it is open interrupting the circuit of which they form a part, one of said 85 cooperating contacts being a spring arm which is pivoted to the casing to swing to and from a position for holding said door closed.

90 5. In a device of the class described, a current interrupting mechanism including a rotary distributor head, a two-armed contact making and breaking member which cooperates with said head; and a terminal with which one of the arms of said two-armed member cooperates, said casing having a door which forms a part of the wall thereof, said two-armed member and said terminal being 95 attached to said door to move therewith into and out of operative position.

100 In testimony whereof I hereunto affix my signature.

CHARLES W. HUNTER.
